UNITED STATES PATENT OFFICE.

CHARLES B. McDONALD, OF CHICAGO, ILLINOIS.

BAIL-EAR FOR METALLIC VESSELS.

SPECIFICATION forming part of Letters Patent No. 746,783, dated December 15, 1903.

Application filed December 17, 1902. Serial No. 135,541. (No model.)

To all whom it may concern:

Be it known that I, CHARLES B. McDONALD, a citizen of the United States, residing at Chicago, in the county of Cook and State of Illinois, have invented certain new and useful Improvements in Bail-Ears for Metallic Vessels, of which the following is a specification.

My invention relates to bail-ears for metallic vessels; and its object is to provide a new and improved device of this character which may be attached to metallic vessels without leaving an opening for the escape of the contents thereof.

In the drawings accompanying this specification and forming a part thereof, Figure 1 is a sectional view of a metallic vessel provided with my invention. Fig. 2 is an enlarged sectional view through the bail-ear of Fig. 1. Fig. 3 is a detail view of the inside 20 of the vessel, showing the parts of the bail-ear as they appear when assembled, being taken on the line 3-3 of Fig. 2; and Fig. 4 is a detail of the outside of the bail-ear, being the reverse of Fig. 3 and being taken on the 25 line 4-4 of Fig. 2.

Referring to the drawings, the numeral 1 denotes a metallic vessel, such as a lard-pail, for example, provided with a suitable handle or bail 2, these parts being of any desired size 30 and shape. The vessel is provided with opposite circular openings, each having an in-turned flange or wall 3, providing a seat adapted to receive a correspondingly-shaped cup 4. The bottom of the cup is closed, and 35 the edge or rim of its mouth is provided with a flange 5, which seats within a recess or depression 6, surrounding the corresponding flange at the opening in the pail. The cup is seated within its associated seat and is held 40 firmly therein by the friction of the body of the cup upon the flange 3, which surrounds the opening and in which the cup is pressed. The cup makes a close fit within its seat, being driven therein by any suitable means, as 45 a press, which at the same operation will spread or upset the metal of the cup against the seat, as by suitably indenting the bottom wall of the cup in order more securely to hold the cup within its seat. The edge or rim 5 of 50 the cup limits its extent of entrance into the

opening and is flush with the outside face of the body of the pail, and its body portion forms a closure to effectually seal the opening in which it rests against any escape of the contents of the pail.

The cup 4 receives an inner cap 7 in the form of an annular cup and whose body is in the form of a circular flange 8, which is pressed within the open mouth of the cup, with its flange in frictional engagement with the inner face of the body of the cup, whereby the cap is locked in place. The face of the cap is preferably slightly bulged, as shown, and is provided with a suitable perforation 9 to receive the end of the handle, as shown in Fig. 1. The cap is preferably fitted within the cup before the latter is inserted within its seat, whereby the pressure on the flange 5 of the cup when the latter is driven to place, as by a suitable press, serves to crowd the metal against the cap to more securely hold it in place. The parts of the ear are held in place by the friction of their contacting surfaces, and the ear in turn is held in the seat of the vessel by friction with its seat or in-turned flange 3. This form of joint provides three friction-surfaces, and as the coacting flange 3, the body of the cup 4, and the body or flange 8 of the cap are all made by drawing the metal in suitable draw-rings the coacting surfaces are perfectly true and have a smooth finish. The cup telescopes within its seat, and the cap in turn telescopes within the cup, whereby the parts are easily and quickly assembled without any manipulation in adjusting them and are held securely in position. The seats for the ears are in-turned, whereby the exterior surface of the pail or vessel presents a smooth finish.

Having described my invention, what I claim, and desire to secure by Letters Patent, is—

1. In a metallic vessel, the combination of a body having opposite openings provided with in-turned flanges, cups seated in the openings in engagement with the flanges, and caps held in the cups and provided with bail-attaching means.

2. In a metallic vessel, the combination of a body having openings provided with in-

turned flanges, cups having their bodies seated on the flanges of the openings, and caps having flanges seated in the cups.

3. In a metallic vessel, the combination of
5 a body having openings provided with in-turned flanges and recesses about the flanges, cups seated on the flanges and having lateral flanges resting in the recesses, and caps hav-

ing flanges seated in the cups and provided with openings.

In testimony whereof I affix my signature to
in presence of two witnesses.

CHARLES B. McDONALD.
